UNITED STATES PATENT OFFICE.

FREDERICK C. WHITMORE, OF NEW YORK, N. Y.

AUTOMOBILE SIGNAL.

Application filed April 1, 1926. Serial No. 99,106.

The invention relates to improvements in turning and stop signals for automobiles and has reference more particularly to those of the type which are actuated by suction from the intake manifold of the motor, or some other part in which a partial vacuum exists.

In carrying out my invention, I make use of a vertically elongated casing in which a signaling arm is normally disposed, said arm being pivotally mounted for outward swinging to signaling position, and I employ a bellows connected with the arm for outwardly swinging the latter, and one object of the invention is to provide an exceptionally compact relation of arm, bellows and casing, permitting the latter to be of slight width.

An illuminating bulb is provided for the signaling arm, and a further aim of the invention is to provide the bellows with co-acting relatively fixed and movable contacts for automatically completing the circuit of this bulb when the arm is projected, the circuit being broken when the arm again moves into the casing.

A still further object is to provide a construction of extreme simplicity and one which may therefore be manufactured and sold at small cost, yet will be efficient and in every way desirable.

With the foregoing in view, the invention resides in the novel subject matter herein-after described and claimed, the description being supplemented by the accompanying drawing.

Figure 1 is a vertical sectional view through a signaling device constructed in accordance with my invention, a portion of the signaling arm being shown in elevation, this arm being disposed in its normal position, within the casing.

Figure 2 is a detail sectional view showing the manner in which collapse of the bellows projects the signaling arm and completes the circuit for its illuminating bulb.

Figure 3 is a horizontal sectional view substantially on line 3—3 of Figure 1.

In the drawings above briefly described, the numeral 3 designates a vertically elongated casing preferably formed from sheet metal and provided with an open outer side 4, while all other vertical sides of said casing and its top are closed so as to protect internal parts from the elements as much as possible. This casing may be mounted in any desired manner and for illustrative pur-

poses, its lower end is provided with an outstanding flange 5 to be secured by bolts or the like 6 upon an automobile fender 7, with the open casing side 4 disposed toward the outer edge of the fender.

Normally hanging vertically in the casing 3, is a signaling arm 8, the upper end of said arm being pivoted to the opposed casing sides, upon a shaft 9 or other desired pivotal mounting means. This arm 8 is outwardly spaced from the inner side wall 10 of the casing 3, to a sufficient extent to permit the mounting of a bellows 11 in the space between said arm and the wall. This bellows is vertically disposed and has its stationary side wall 12 secured in any suitable manner against the inner surface of the wall 10, while the movable side wall 13 of said bellows is connected by a link 14 with a portion of the arm 8, above the pivot 9. Thus, when the bellows 11 is collapsed as shown in Figure 2, it will swing the signaling arm 8 outwardly through the open side of the casing 3.

The arm 8 is preferably provided at its front and rear sides, with translucent panels 15 of any desired color, and an illuminating bulb 16 is provided for these panels to impart a conspicuous, mellow glow to them each time the arm 8 is extended, and to complete the circuit of this bulb, coacting contacts 17 and 18 are preferably carried by the fixed and movable walls 12 and 13 of the bellows 11, which walls are shown projecting beyond the flexible portion 19 of said bellows, to carry said contacts.

The contact 17 is preferably in the form of a coiled spring while the contact 18 may well be a metal plate disposed at the inner side of the wall 13. In the present showing, fasteners 20 pass through the free end portion of the wall 13, through the plate 18, and through another metal plate 21 at the opposite side of said wall and electrically connect said plates 18 and 20. To this plate 21, the link 14 is connected by a metallic pivot 22, and said link is also of metal. The opposite end of this link is pivoted to the arm 8 as indicated at 23, but is insulated from said arm, if the latter be of metallic construction. From the link 14, I have shown a wire 24 connected to the socket 25 for the bulb 16, and also connected to this socket, is a wire 26. The contact 17, being electrically connected with casing 3 and the

latter being secured upon the fender 7, said contact receives current from the positive lead 27 of the usual battery 28, and the wire 26 is either connected with the negative lead 5 29 of the battery or leads directly to the negative terminal of the latter. Thus, as soon as the contact plate 18 strikes the spring 17 upon collapse of the bellows, current flows through these two contacts, 10 through the fasteners 20 and plate 21, to the pivot 22, then through the link 14 and the wire 24 to the socket 5, and from this socket the current returns through the wire 26, said current of course passing through the filament of the bulb 16 to illuminate the latter. It will thus be seen that immediately upon projection of the signaling arm, the illuminating bulb will be brought into play, whereas this bulb will be extinguished as 15 soon as the arm is again swung into the casing.

Any desired construction may be employed for the signaling arm 8. For illustrative purposes, this arm is shown as formed of 25 upper and lower casing sections 30 and 31 detachably connected by screws 32, and an insulating base 33 is shown secured within the lower end of the casing section 30 to carry the socket 25. By removing the screws 30 32 and detaching the lower section 31, access may be had to bulb 16, for replacing it whenever necessary, with a new bulb.

The upper end of the casing section 30 preferably has its inner half offset from its 35 outer half, providing an upwardly projecting corner portion 34. This corner portion is formed with a notch 35 through which the link 14 passes, in the present showing, the pivotal connection 23 being within the 40 casing section 30.

As excellent results may be obtained from the general construction shown and described, it may well be followed. However, it is to be understood that within the scope 45 of the invention as claimed, numerous variations may be made, and while I contemplate connecting the bellows 11 with the intake manifold and the provision of a suitable control valve, it is to be understood that 50 other means could be employed if desired,

for creating suction in said bellows to collapse it.

I claim:

1. A signaling device comprising a casing having an open outer side, a signaling arm 55 pivotally mounted in said casing for movement through said open side, a bellows secured in the casing between the inner side wall of the latter and said signaling arm and having a stationary and a movable side 60 wall, the stationary and movable side walls of said bellows being projected beyond the flexible portion of the latter, coacting contacts carried by said projecting portions of the stationary and movable bellows walls 65 and adapted to contact when the bellows is collapsed, a metallic link connecting the movable bellows wall with the signal arm for projecting the latter when the bellows is collapsed, said link having electrical connection with the movable contact, an illuminating bulb for the arm, and means coactive with said contacts and link for completing the circuit of said bulb when the bellows is collapsed and the arm projected. 70

2. A signaling device comprising a casing having an open outer side, a signaling arm pivotally mounted in said casing for movement through said open side, a bulb carried by said arm, a bellows secured in the casing between the inner side wall of the latter and said signaling arm and having a stationary and a movable side wall, the stationary and movable side walls of said bellows being projected beyond the flexible portion of 85 the latter, coacting contacts carried by said projecting portions of the stationary and movable bellows walls and adapted to contact when the bellows is collapsed, means connected with said movable bellows walls 90 for projecting said arm on the collapse of the bellows, an electrical connection between said bulb and said movable contact, including the means for projecting said arm, whereby the bulb will be lit on the collapsing of the bellows and projection of the arm. 95

In testimony whereof I have hereunto affixed my signature.

FREDERICK C. WHITMORE.
